(57) **CLAIM**

The ornamental design for a bottle, as shown and described.

DESCRIPTION

FIG. 1 is a front perspective view of a first embodiment of a bottle;

FIG. 2 is a front view of the first embodiment of a bottle shown in FIG. 1;

FIG. 3 is a left view of the first embodiment of a bottle shown in FIG. 1;

FIG. 4 is a right view of the first embodiment of a bottle shown in FIG. 1;

FIG. 5 is a rear view of the first embodiment of a bottle shown in FIG. 1;

FIG. 6 is a top view of the first embodiment of a bottle shown in FIG. 1;

FIG. 7 is a bottom view of the first embodiment of a bottle shown in FIG. 1;

FIG. 8 is a front perspective view of a second embodiment of a bottle;

FIG. 9 is a front view of the second embodiment of a bottle shown in FIG. 8;

FIG. 10 is a left view of the second embodiment of a bottle shown in FIG. 8;

FIG. 11 is a right view of the second embodiment of a bottle shown in FIG. 8;

FIG. 12 is a rear view of the second embodiment of a bottle shown in FIG. 8;

FIG. 13 is a top view of the second embodiment of a bottle shown in FIG. 8; and,

FIG. 14 is a bottom view of the second embodiment of a bottle shown in FIG. 8.

The evenly dashed broken lines in the drawings showing the bottle structure illustrate the portions of the design that form no part of the claim. The dot-dot-dash broken lines in the drawings define the bounds of the claim and form no part thereof.

The closely placed repeating horizontal broken lines applied to the claimed portion of the drawings in FIGS. 1–4 represent the colors gray or silver and are intended to be part of the claimed design.

1 Claim, 6 Drawing Sheets
